IMPULSE CLOCK

Filed Aug. 16, 1930

UNITED STATES PATENT OFFICE

ROY F. SMITH, OF EL PASO, TEXAS, ASSIGNOR OF ONE-HALF TO WILLIAM FRED KITCHENS, OF EL PASO, TEXAS

IMPULSE CLOCK

Application filed August 16, 1930. Serial No. 475,816.

In electric clock systems of the type in which impulses are transmitted at regular intervals (such as once per minute) to a plurality of secondary clocks which have electro-
5 magnets or other means for advancing the clock-trains one step for each impulse, it is generally known that the secondary clocks sometimes get out of step with the master clock and various schemes have been devised
10 to correct the secondary clock at regular intervals (say once per hour). One scheme for effecting this result consists in providing a stop for physically obstructing each clock-train at regular intervals (say once per hour)
15 if the clock is fast, with means for automatically removing the stop on the hour so that the clock-train may resume its advance after it has been retarded the required amount. In order to correct slow secondaries it has been
20 proposed to transmit a series of fast impulses just before the end of the hour rapidly to advance the secondaries until the stops obstruct further advance, further movement of the clock-trains being permitted by automatic re-
25 moval of the stops at the end of the hour.

One of these schemes have been entirely satisfactory, an outstanding objection consisting in that the ratchet or other means moving back and forth to advance the clock-
30 train creates an objectionable noise after the clock-train has been obstructed by the afore-
said stop due to the fact that the back-and-forth movement continues after the stop be-
35 comes effective and inasmuch as the clock-train can not be advanced by the ratchets the latter noisily pound against the stationary ratchet wheel. The objects of the present in-
40 vention are to prevent the aforesaid chatter-
ing and generally to improve the construction and operation of secondary clocks of the im-
pulse type.

For the purpose of illustrating the genus of this invention a typical embodiment is
45 shown in the accompanying drawing in which

Fig. 1 is a rear view of the clock mechanism, parts being broken away;

Fig. 2 is a similar view showing the parts in a different position;

50 Fig. 3 is a top plan view of the mechanism;

Fig. 4 is a rear elevation of the stop and associated weight;

Fig. 5 is a circuit diagram illustrating one method of operation; and

Fig. 6 is a similar circuit diagram illustrating another wiring arrangement.

The particular embodiment of the invention shown for the purpose of illustration comprises two ratchet wheels 1 and 2 with associated pawls 3 and 4. The ratchet wheels 60 1 and 2, which are fastened together and to the shaft 5, have their teeth facing in opposite directions; the ratchet 3 turns the wheels in a clockwise direction while the pawl 4 holds the wheels against retrograde movement 65 while the pawl 3 is being retracted. The pawl 3 is carried on an arm 6 pivoted at 7, arm 6 being provided with a stop 8 engageable with the teeth of wheel 1 to present overthrow by pawl 3. The pawl 3 is retracted by a mag- 70 net 9 operative upon armature 10 fast to arm 6 and after the magnet is deenergized the pawl is again advanced by spring 11. All of these parts are standard equipment and the novel parts which constitute the illustrative 75 embodiment of the present invention will now be described.

A ring 12, of metal or other material having appreciable weight, is slidably mounted on the rear face of the ratchet wheel 1 by 80 means of two pins 13 and 13' extending axially from the wheel through slots 14 and 14' in the ring with heads on their outer ends to retain the ring. The pins 13 and 13' are so located that the ring may slide back and 85 forth throughout a limited range along the diameter of the wheel extending through the pins. Fast to the ring near the slot 14 is a stop 15 which extends outwardly beyond the outer periphery of the ring and ratchet wheel 90 1 and then hooks forwardly a distance sufficient to overhang the stop 8 in one of the sixty positions of the ratchet wheel and ring. The stop 15 is so adjusted that when the closed end of slot 14 rests upon the pin 13 the overhanging portion 16 of the stop is in close juxtaposition to the upper surface of the stop 8 so that the pawl 13 can not be lifted an appreciable distance without also lifting the weight 12 (Fig. 2). In order to lift the stop 100

15 so that it will pass to a position over the stop 8 in one of the sixty steps of the mechanism during each cycle, a pin 17 is mounted on the weighted ring 12 to engage a stationary cam 18. As the stop 15 approaches the stop 8 the cam 18 acting on the pin 17 gradually moves the stop 15 farther away from the axis of the shaft 5 and when the stop 15 reaches a position over the stop 8 the pin 17 drops off the toe 19 of the cam 18 thereby permitting the overhanging portion 16 of the stop 15 to drop into close juxtaposition to the stop 8.

A second pin 17' similar to pin 17 may if desired be provided at a point on the ring approximately opposite the location of the pin 17 to prevent the center of gravity of the weighted ring from shifting to the left of the vertical plane of the shaft 5 during the first half of each cyclic movement of the parts inasmuch as such a shift of the center gravity might cause the ratchet wheel to overthrow. (Obviously no such tendency exists as long as the center gravity of the weighted ring is to the right of the action of the shaft 5.)

The operation of the clock is as follows: If the clock is fast the stop 15 will lock the arm 6 in the position shown in Fig. 1 before the end of the hour (according to the master clock) and the clock will remain stationary until the end of the hour. During this stationary period the pawl 3 and associated parts can not chatter back and forth because held by the stop 15. If the clock is slow it is brought to the stop position by a series of fast impulses transmitted to the magnet 9 by the master clock just before the end of the hour. Means for transmitting such impulses are disclosed in the Keilien applications Serial Nos. 341,176 and 341,177 filed February 19, 1929 and is not here reproduced as it is unnecessary for a clear understanding of the present invention. Advance of the clock-train is resumed at the end of the hour by transmitting to the magnet 9 an impulse of sufficiently increased magnitude to lift the weighted ring 12. A suitable arrangement for transmitting such an impulse is also disclosed in the aforesaid Keilien applications. Inasmuch as a single impulse of increased magnitude moves the overhanging portion 16 of the stop 15 beyond the stop 8 only a single impulse of increased magnitude is required once per hour (or other predetermined interval). Obviously the increased force applied to the arm 6 to lift the weighted ring may be produced in a great many ways as for example by increasing the current to the single winding of magnet 9 or providing two windings on magnet 9, only one of which is utilized in normally advancing the clock and both of which are utilized additively in producing the impulse of increased magnitude (Fig. 6), etc.

It should be understood that the present

disclosure is for the purpose of illustration only and that this invention includes all modifications and equivalents which fall within the scope of the appended claims.

I claim:

1. A secondary clock having a clock-train and comprising driving means movable back and forth for advancing the clock-train step by step in response to impulses from a master clock, and resetting means in the clock for automatically rendering said driving means ineffective at predetermined intervals, said resetting means including a stop for physically obstructing said back-and-forth movement. 70

2. A secondary clock having a clock-train and comprising driving means movable back and forth for advancing the clock-train step by step in response to impulses from a master clock, and resetting means in the clock for automatically rendering said driving means ineffective at predetermined intervals, said resetting means including a stop for physically obstructing said back-and-forth movement at a predetermined point in the cyclic movement of the clock-train. 80

3. A secondary clock having a clock-train and comprising driving means movable back and forth for advancing the clock-train step by step in response to impulses from a master clock, and resetting means in the clock for automatically rendering said driving means ineffective at predetermined intervals, said resetting means including a stop for physically obstructing said back-and-forth movement, and means responsive to an impulse from the master clock for removing said stop after the clock has been reset. 90

4. A secondary clock having a clock-train and comprising driving means movable back and forth for advancing the clock-train step by step in response to impulses from a master clock, and resetting means in the clock for automatically rendering said driving means ineffective at predetermined intervals, said resetting means including a stop for physically obstructing said back-and-forth movement, and means responsive to an impulse from the master clock for removing said stop after the clock has been reset, said last means including a non-polarized electromagnet. 100

5. A secondary clock having a clock-train and comprising a ratchet for advancing the clock-train step by step in response to impulses from a master clock, and resetting means in the clock for automatically rendering said ratchet ineffective at predetermined intervals, said resetting means including a stop for physically obstructing back-and-forth movement of the ratchet. 110

6. A secondary clock having a clock-train and comprising a ratchet for advancing the clock-train step by step in response to impulses from a master clock, and resetting

- means in the clock for automatically rendering said ratchet ineffective at predetermined intervals, said resetting means including a stop actuated by said ratchet for physically 5 obstructing the back-and-forth movement of the ratchet at a predetermined point in the cycle movement of the clock-train.
7. A secondary clock having a clock-train and comprising a ratchet for advancing the 10 clock-train step by step in response to impulses from a master clock, resetting means in the clock for automatically rendering said ratchet ineffective at predetermined intervals, said resetting means including a stop 15 for physically obstructing the back-and-forth movement of the ratchet, and means responsive to an impulse from the master clock for removing said stop after the clock is reset.
8. A secondary clock having a clock-train 20 and comprising a ratchet for advancing the clock-train step by step in response to impulses from a master clock, resetting means in the clock for automatically rendering said ratchet ineffective at predetermined intervals, 25 said resetting means including a stop for physically obstructing the back-and-forth movement of the ratchet, and means responsive to an impulse from the master clock for removing said stop after the clock 30 is reset, said last means including a non-polarized electromagnet.
9. A secondary clock having a clock-train and comprising a ratchet and ratchet wheel 35 for advancing the clock-train step by step in response to driving impulses from a master clock, and a stop operative at a predetermined point in each cycle of the clock-train for holding the ratchet against retraction by normal driving impulses, the stop being movable from holding position by the ratchet in 40 response to an impulse of increased magnitude.
10. A secondary clock having a clock-train and comprising a ratchet and ratchet wheel 45 for advancing the clock-train step by step in response to driving impulses from a master clock, a weighted stop mounted on the ratchet wheel to slide radially in one dimension of the wheel for holding the ratchet against retraction by normal driving impulses at a predetermined point in each cycle of the clock-train, the stop being movable from holding position by the ratchet in response to an impulse of increased magnitude.
- 55 11. Secondary clock having a clock-train and comprising a ratchet and ratchet wheel 50 for advancing the clock-train step by step in response to driving impulses from a master clock, a weighted stop mounted on the ratchet wheel to slide radially in one dimension of the wheel for holding the ratchet against retraction by normal driving impulses at a predetermined point in each cycle of the clock-train, the stop being movable from holding position by the ratchet in response to 65
- an impulse of increased magnitude, and means for camming said stop to retracted position as the clock-train approaches said predetermined point and then dropping the stop to holding position when the clock-train reaches said point.
12. A secondary clock comprising a ratchet and ratchet wheel for advancing the clock-train step by step in response to driving impulses from a master clock, a stop operative 70 at a predetermined point in each cycle of the clock-train for holding the ratchet against retraction by said driving impulses, and means responsive only to other impulses from the master clock for moving the stop from holding position.
